UNITED STATES PATENT OFFICE.

WILLIAM P. HART, OF SOUTHBRIIDGE, MASSACHUSETTS, ASSIGNOR TO DRAPER CORPORATION, OF HOPEDALE, MASSACHUSETTS, A CORPORATION OF MAINE.

SHUTTLE-TENSION DEVICE.

Application filed December 27, 1923. Serial No. 682,961.

To all whom it may concern:

Be it known that I, WILLIAM P. HART, a citizen of the United States, residing at Southbridge, in the county of Worcester and State of Massachusetts, have invented a certain new and useful Improvement in a Shuttle-Tension Device, of which the following is a specification.

My invention relates broadly to loom 10 shuttles, and more particularly to a thread tension device for use in loom shuttles.

One of the objects of my invention is to provide a tension device for automatic threaders which may be adjusted according 15 to the kind of yarn or thread carried by the bobbin in the shuttle to impart the degree of tension required for such different materials.

Another object of my invention is to 20 provide a removable tension device which may be readily inserted in various constructions of automatic threaders and adjusted in position according to the properties of the thread used in the loom.

25 A further object of my invention is to provide a tension device for automatic threaders comprising a cylindrical body having a thread groove therein provided with parallel walls extending throughout a portion of the groove and angularly disposed walls adjacent the parallel walls to 30 guide the thread into the groove or slot.

Still another object of my invention is to provide a replaceable insert for automatic threaders having a surface treated in such manner that the thread running therover will have the proper tension imparted thereto for securing the best results with given weights and twists of yarn in the 40 weaving of cloth.

My invention also contemplates the provision of means for locking the adjustable tension device in a selected position after the particular position has been determined 45 for the given weight and twist of the thread with which it is employed.

Other and further objects of my invention will be understood from the specification which follows when read in connection 50 with the accompanying drawings, in which:

Figure 1 is a perspective view of a loom shuttle showing the application of my adjustable tension device thereto; Fig. 2 is an enlarged front elevation of an automatic threader showing the adjustable ten-

sion device of my invention carried therein; Fig. 3 is a fragmentary view partially in section showing a shuttle, an automatic threader carried therein, and the arrangement of my adjustable tension device in the automatic threader; and Fig. 4 is a cross sectional view of a modified form of my adjustable tension device having its surface treated for particular weights or kinds of threads or yarns which may be carried by the bobbin 60 within the shuttle.

The form of my invention illustrated in the drawings and hereinafter described in detail constitutes one of the practical embodiments of the invention capable of efficient operation. In the art of weaving cloth the yarn may have a right or left hand twist. The yarn may also be wound on the bobbin in either a right or left hand direction. In the operation of shuttles in the weaving process if yarn which has a right hand twist is subject to a force which imparts to it a left hand twist, the yarn results in an unbalanced twist, giving it 75 a kinky formation. Kinky yarn is difficult 80 to place under proper tension. Normally, when the yarn is unwinding from the bobbin in the shuttle it follows a rotary path. There is potential energy stored in the yarn on the bobbin which is transformed to kinetic energy as the yarn rotates or unwinds from the bobbin. The forces acting upon the thread as it unwinds from the bobbin may tend to throw the thread upwardly 85 out of the automatic threader. The adjustable tension device of my present invention has been designed to overcome or reduce the kinetic energy or centrifugal force in the path of the travel of the yarn and to prevent the yarn from leaving the threader. 90

The tension device may be adjusted to accommodate thread that is twisted in either a right or left-hand direction, and it may also be adjusted to position its slot at various angles relative to the walls of the thread 100 channel of the automatic threader to increase or decrease the path of resistance. By overcoming the centrifugal force or kinetic energy expended by the yarn, I reduce the tendency of the yarn to become kinky. 105 The centrifugal force or kinetic energy expended by the yarn varies directly with the velocity of the shuttle in motion. The greater the velocity, the larger the force which the yarn imparts to the walls of the 110

channel and correspondingly the harder that the yarn hits, the greater will be the force acting against the centrifugal force serving to neutralize the same. The centrifugal force also increases as the velocity of the shuttle increases.

A proportional force is brought into play as the thread hits the walls of the channel, thereby balancing the forces in the thread and also balancing the twist. In the operation of the loom a certain magnitude of force is applied to the shuttle to move it across to the opposite shuttle box, and when the shuttle hits the side walls of the shuttle box it imparts some of the kinetic energy possessed by the shuttle to some of the yarn, changing the potential energy in some of the yarn to kinetic energy as the yarn is released from the bobbin. The tension device of my invention operates to retard the progress of the yarn caused by this sudden shock.

Broadly, my adjustable tension device comprises a slotted member which may be inserted in the automatic threader. The slot of said member is provided with substantially parallel walls and has angularly disposed walls for directing the thread into the slot. The tension device may be rotated in the automatic threader in either direction, depending upon the direction of rotation of the yarn and the direction of twist. When the position of the tension device has been selected for the particular kind of thread or yarn employed, it is secured in the selected position by an adjusting screw. It will be understood that the angular position of the tension will vary for cotton, woolen, or other material. I may also treat the surface of the tension device to secure more efficient operation for the different materials having different characteristics and properties.

Referring now more particularly to the drawings, 1 indicates a shuttle containing a block or automatic threader 2 having a thread passage 3. My adjustable tension device 4 is shown as positioned in the block or automatic threader 4, and comprises a cylindrical member having a slot or channel 5 running longitudinally through the body thereof and provided with walls 6 and 7 in parallel relationship and extending in the direction of the travel of the thread. Adjacent the entrance to the thread channel 5 the walls are angularly disposed, as indicated at 14 and 15, to direct the thread into the channel. The tension device may be rotated within the threader 2 to cause the channel to assume different angular positions.

In Fig. 2 I have represented the direction of the yarn as it unwinds from the bobbin with rotary motion by means of the full line arrow 9. When the yarn rotates from

the bobbin in this clockwise direction the tension device is set in the full line position disposed toward the right. If the yarn is rotating in the direction indicated by the dotted line arrow 10, the tension device is moved in a counter-clockwise direction and set in dotted line position 8. The position of the tension device is varied and selected for particular weights and kinds of yarn and thread and then set by means of screw 11. Access is obtained to the adjusting screw 11 through an aperture 12 in the shuttle.

For different kinds of yarns and threads I may construct the tension device of different types of material, such as steel, fiber, porcelain, or glass. I have determined that hardened steel operates better as a tension device for cotton while steel glazed over with vitreous matter, as represented at 16 in Fig. 4, operates better with woolen yarns which require minimum tension by reason of its characteristic relatively heavy weight.

It will be understood that the tension device is adjustable by small angular increments to selected positions to give maximum or minimum tension. The weight and twist of different yarns varies so that it is necessary to vary the position of the tension device accordingly to secure the best results in the weaving of cloth. The kinetic energy existing by reason of the travel of the yarn expends itself against the hard walls of the tension device whereby a continuously running balanced weave is obtained.

While I have described my invention in certain particular embodiments, it is to be understood that modifications may be made and that I intend no limitations upon the inventions other than are imposed by the scope of the appended claims.

What I claim and desire to secure by Letters Patent of the United States is as follows:

1. An automatically threading loom shuttle having a thread passage, a tension device adjustably mounted in the thread passage to rotate about an axis extending longitudinally of the shuttle to present the thread contacting walls thereof in different position that the tensioning effect on the thread may be varied, and means for securing the tension device in different positions of angular adjustment within the thread passage.

2. An automatically threading loom shuttle having a thread passage, a tension device adjustably mounted in said passage to turn about an axis extending longitudinally of the shuttle and provided with a slot, and means for securing the tension device in different positions of angular adjustment within the thread passage to present the thread contacting walls of the slot in different positions and thus vary the tensioning effect upon the thread passing through the tensioning device.

3. In a shuttle, the combination of a threading block having a thread passage, a tension device having a thread receiving opening and adjustably mounted in the block to turn about an axis extending longitudinally of the shuttle to present the thread contacting walls of the opening at different angles that the effect upon the thread may be varied, and means for securing the tension device in different positions of angular adjustment within the thread passage. 55
4. In a shuttle, in combination, a threading block having a thread passage, a tension device comprising a cylindrical member adjustably mounted in the thread passage and provided with a thread receiving slot, means for supporting the tension device for rotation about an axis extending longitudinally of the shuttle to vary the angular disposition of the thread engaging walls of said slot and the consequent effect upon the thread passing therethrough, and means for securing the tension device in different positions of angular adjustment. 60
5. In combination with a shuttle having a thread passage extending longitudinally of the shuttle, a tension device mounted for rotation about an axis extending longitudinally of the shuttle and having a slot for receiving a thread, and means for securing the tension device in different positions of adjustment about said axis so that the slot may be turned to present its entrance toward either side wall of the thread passage to facilitate entrance of the thread thereto in accordance with the whirl of the thread. 70
6. In combination with a shuttle having a thread passage extending longitudinally of the shuttle, a tension device mounted in said passage for rotation about an axis extending longitudinally of the shuttle and having a slot for receiving a thread, a vitreous material upon the walls of said slot, and means for securing the tension device in different positions of angular adjustment about said axis to present the thread contacting walls of the slot in different positions and to accommodate the tension device to the character of the thread in use. 75
7. An automatically threading loom shuttle having a threading block provided with a thread passage, a tension device having a thread receiving opening and mounted for rotative movement about an axis extending longitudinally of the thread passage to present the walls of the opening for varied engagement by the thread, and means for securing the tension device in adjusted position and in accordance with the properties of the thread being used. 80
8. An automatically threading loom shuttle having a thread passage, and a tension device having a thread receiving slot and mounted for rotative adjustment about an axis extending longitudinally of the shuttle to present the thread contacting walls of the slot in different positions for engagement by the thread that the tensioning effect may be varied. 85
9. An automatically threading loom shuttle having a thread passage, a tension device having a thread receiving slot provided with a flaring entrance and mounted for rotative adjustment about an axis extending longitudinally of the shuttle to present the flaring entrance to the thread in accordance with its direction of rotation, and means for securing the tension device in adjusted position. 90
10. An automatically threading loom shuttle having a thread passage, a thread tensioning device having a thread receiving opening and mounted for adjustment about an axis extending longitudinally of the shuttle to present the opening for the entrance of the thread in accordance with the direction of its whirling action and present the thread engaging walls in different inclinations to vary the tension in conformity with the properties of the thread in use. 95
11. An automatically threading loom shuttle having a thread passage, a tensioning device having a thread passage opening upwardly and mounted for adjustment about an axis extending longitudinally of the shuttle to present the thread engaging walls of the tensioning device in a direction inclined toward either side of the shuttle to vary the tensioning effect upon the thread passing therethrough. 100
